UNITED STATES PATENT OFFICE.

RUDOLF VON FROMMER, OF BUDAPEST, HUNGARY.

SAFETY MECHANISM FOR FIREARMS.

Application filed August 10, 1926, Serial No. 128,496, and in Hungary August 14, 1925.

This invention relates to safety mechanisms for firearms of the kind, the firing pin of which is rotatable in the breech-bolt and is provided with a knob or the like 5 on its rear end by means of which the firing pin may be turned into its safety position.

According to the present invention the firing pin or some part of the gun connected therewith, for example the firing pin nut, 10 is provided with a projection and the breech casing with a groove, or the breech casing is provided with a projection and the other part of the gun with a groove, so that in the rear position of the firing pin the projection 15 may be turned into the groove, the firing pin being thereby secured in its rear position.

In the accompanying drawing one form 20 of the mechanism according to the invention is diagrammatically shown by way of example.

Fig. 1 is a horizontal, longitudinal sectional view of the breech bolt, the breech casing and part of the barrel, the breech bolt being fully closed.

Fig. 2 shows the tooth of the breech bolt and the notch of the firing-pin-nut in engagement.

Fig. 3 is the same view as Fig. 1 the 30 handle, however, being turned with 90°.

Fig. 4 is a vertical, longitudinal sectional view of the mechanism the firing pin being cocked, while

Fig. 5 is a cross sectional view taken on 35 lines V—V of Fig. 1 the firing pin being secured.

In the breech casing 2 which is connected to the barrel 1 the breech bolt 3 is arranged in a well known manner. The handle 4 of 40 the breech bolt in its closed or turned down position bears with its root-portion 5 against the surface 6 of the breech casing 2 thereby effecting the locking of the breech bolt. The firing pin 7, arranged in the 45 breech bolt is subject to the action of a spring 8 and is screwed together with the firing-pin-nut 9.

According now to the invention there is 50 arranged on the breech bolt 3 a tooth 10 which registers in the closed position of the breech, as in Fig. 1, with the notch 11 provided in the firing-pin-nut, this enabling the firing-pin to discharge the cartridge pushed in the barrel. In every other position of 55 the breech bolt, that is if the handle 4 is not

fully turned down this is an impossibility because the tooth 10 prevents the firing-pin-nut and thereby the firing pin from completing their forward movement (Fig. 3).

For the purpose of preventing an unintentional shooting forward of the firing pin 60 7 or the firing-pin-nut 9 there is arranged on the latter a projection 12 which may be turned into a groove 13 provided in the breech casing 2 by pulling backwards and 65 rotating the firing pin by means of the knob 15, whereby the firing of the gun is made impossible because the groove 13 retains the firing pin by means of the projection 12. If it is desired to terminate the 70 locking of the firing pin the projection 12 is turned out from the groove 13 and is let gently forward.

In order to prevent the projection 12 from accidentally turning out from the 75 groove 13 the latter is provided with a notch 14 (Fig. 4) which is formed on the front side of the groove, and joins at its top side, at 17, the bore of the breech casing (Fig. 5). In other words the notch 14 is not open 80 while the groove 13 is open for permitting of the projection 12 to be turned into the groove. By pulling now the firing pin backwards and releasing it after turning into the groove 13 the firing spring 8 will 85 press the projection 12 of the firing pin in the notch 14 which as it is not open will not allow the projection to turn out. For releasing the projection 12, that is to say the firing pin, the same is first to be slightly 90 drawn backwards so that the projection 12 may again enter the groove 13 wherefrom it may be turned out. The projection 12 beside that above mentioned, has another function that of guiding the firing-pin-nut 95 which function is performed by its being guided in the slot 16 in which the root-portion 5 of the handle 4 is guided in a well known manner.

Obviously, the tooth 10 and its corresponding notch 11 might be reversely arranged, that is to say the tooth may be provided on the firing-pin-nut and the notch on the breech bolt. In the same manner the projection 12 and the groove 13 may also be reversely arranged, that is to say the groove on the firing-pin-nut and the projection on the breech casing. One of the two engagement elements may be arranged instead of on the firing-pin-nut on the firing- 100 105 110

pin itself, or on any other part of the weapon connected to the firing pin.

Claims:—

1. In firearms of the kind described a breech casing and a firing pin the said firing pin having a projection and the said breech casing having a groove means on the said firing pin to turn its projection in the said groove in the pulled back position of the firing pin.
2. In firearms of the kind described a

breech casing and a firing pin said firing pin having a projection and said breech casing having a groove, said groove being provided with a notch, means on the firing pin 15 to turn its projection in the said notch of the groove in the pulled back position of the firing pin substantially as described.

In testimony whereof I have affixed my signature.

RUDOLF v. FROMMER.
